ATTORNEY

UNITED STATES PATENT OFFICE.

FELIX MOSER, OF HOLLAND, MICHIGAN.

SOUND RESONATOR FOR PIANOS.

Application filed November 16, 1921. Serial No. 515,483.

To all whom it may concern:

Be it known that I, FELIX MOSER, a citizen of the United States, residing at Holland, in the county of Ottawa and State of Michigan, have invented certain new and useful Improvements in Sound Resonators for Pianos.

The following is a specification, reference being had therein to the accompanying 10 drawings.

My invention relates to sound resonators for grand and upright pianos. Its object is to increase and improve the volume and quality of tone of the piano.

15 The invention consists of the matters herein described and pointed out in the claims.

In the accompanying drawing, Fig. 1 represents the face or sounding-board side of the resonator; Fig. 2 is a cross-section on the 20 line 1—1 of Fig. 1; Fig. 3 is a cross-section on the line 2—2 of Fig. 1; Fig. 4 shows the resonator placed in an upright piano; Fig. 5 shows the resonator placed in a grand piano, and Fig. 6 is a cross-section on the line 25 3—3 of Fig. 5.

The theoretical outline of the resonator is substantially pear-shaped being defined by part of a large circle 6 and part of a small circle 6^a connected by two tangential 30 straight lines 6^b. The size of the circles is determined by the size of the instrument the resonator is to be placed into, and its outline or contour may be modified to fit the particular size and scale of the piano.

35 The face or sounding-board side 8 of the resonator is provided with two round or oblong soundholes 4 and 5, the larger one 4 being located in or near the center of the large circle 6, and the smaller one 5 in or 40 near the center between the two circles. The reverberator side of the resonator consists of a straight or convex back 7 formed of laminated hard wood, such as maple. The sounding-board 8 and reverberator 7

are connected by a rim 9 of laminated wood 45 which may be narrower at the right hand or treble side as shown in Fig. 3, thus forming the resonator. The sounding-board 8 and the reverberator are stiffened by cross-ribs 10. 50

The resonator is placed into the back or frame 11 of an upright piano (Fig. 4), bracing and stiffening the same and then being a part thereof. When placed in a grand piano (Fig. 5) the resonator takes 55 the place of the back to a great extent, the outside rim 12 being glued to it; its outline conforms to the inward curve 12^a on one side and is somewhat widened towards the front 13 to take in the usual and necessary 60 back-bar 14 peculiar to grand piano construction. This back-bar then forms part of the front of the resonator in a grand piano as is shown in Fig. 6. The outline is further modified at the right side forming a 65 corner 14^a in the grand piano, and the same modification is made near the upper right hand corner 15 of the upright piano as in Fig. 4. In Figs. 1, 2 and 3 the bridges 16 and 17 are omitted as they are located differently in an upright and in a grand piano, 70 but they are shown in their usual locations in Figs. 4 and 5.

I claim:

A sound resonator for pianos comprising 75 a ribbed front sounding-board and a ribbed reverberator of hard wood, and having a contour described by opposite sections of relatively large and small circles connected 80 by tangential lines, a laminated rim connecting the edges of the reverberator and sounding-board, and the sounding-board having sound holes located respectively at the center of its larger circle and between the two circles. 85

In testimony whereof I affix my signature.

FELIX MOSER.
